United States Patent Office

Des. 209,362
Patented Nov. 21, 1967

209,362

ELECTRIC TOASTER OR THE LIKE

Earl E. Sutton, Mansfield, and Richard B. Hall, Akron,
Ohio, assignors to Dominion Electric Corporation, a
corporation of Ohio

Filed Jan. 13, 1967, Ser. No. 5,415

Term of patent 14 years

(Cl. D81—10)

Fig. 2

Fig. 3

Fig. 4

Fig. 5

FIGURE 1 is a perspective view of an electric toaster embodying our design;

FIGURE 2 is a plan view of the same;

FIGURE 3 is a bottom view of the same;

FIGURE 4 is a left-hand end view of the same; and

FIGURE 5 is a right-hand end view of the same.

The dominant features of our design are shown in full lines.

We claim:

The ornamental design for an electric toaster or the like, substantially as shown and described.
